UNITED STATES PATENT OFFICE.

JOHAN VALENT, OF WEST HOBOKEN, NEW JERSEY.

GEAR-SHIFTING DEVICE.

1,380,874.

Specification of Letters Patent. Patented June 7, 1921.

Application filed June 5, 1920. Serial No. 386,665.

To all whom it may concern:

Be it known that I, JOHAN VALENT, a citizen of Czechoslovakia, residing at West Hoboken, county of Hudson, and 5 State of New Jersey, have invented certain new and useful Improvements in Gear-Shifting Devices, of which the following is a specification.

The present invention relates to improvements in gear shifting devices and it is the principal object of the invention to provide a device for shifting the gears operating a belt pulley shaft for changing the direction of rotation and for allowing the pulley to 15 run idle if desired.

A further object of the invention resides in the arrangement of the gears within a casing adapted to be partly filled with a lubricating agent so that all parts are 20 constantly kept well lubricated.

Other objects of the invention will become apparent as the description proceeds and will be more fully set forth in the appended claims.

25 In the accompanying drawings—

Figure 1 is a side view of the improved gear shifter after removal of the end plates of the gear casing.

Fig. 2 is a sectional view thereof, this 30 section being taken along line 2—2 of Fig. 1.

Fig. 3 is a sectional view taken along line 3—3 of Fig. 1.

Fig. 4 is a sectional view, the section being taken along line 4—4 of Fig. 2.

35 Fig. 5 is a section through the pulley and its shaft, the section being taken along line 5—5 of Fig. 1, and

Fig. 6 is an end view of the pulley seen 40 from the left of Fig. 5, with the housing partly broken away.

In the drawings, the gear casing is designated at 10, and is provided at its upper part with a hanger 11 by means of which the gear shifter may be suspended from a 45 ceiling or a beam.

In the side walls 12 and 13 of the casing 10 a tubular shaft 14' is journaled in which a longitudinally sliding shaft 14 is located. Both shafts 14 and 14' extend to the outside of the casing and the tubular shaft 14' carries at one of its ends the pulley 15 loosely mounted upon said shaft with its bushing 16. To the opposite end of the shaft 14 a link 17 is pivotally secured with 55 one of its ends as at 18, while the opposite end of said link is pivotally secured as at

19 to a hand lever 20. The upper end of this lever is pivotally secured as at 21 between the prongs of the forked end of a brace bar 22 secured to the outer wall of the casing 60 10 as at 23.

Within the casing the shaft 14' carries a gear wheel 24 secured to said shaft by means of a bushing 25. Below the shaft 14' a frame 26 is secured to the outer wall of 65 the casing on which a plate 27 slides having a central zig-zag-shaped slot 28. To the outer edge of this plate 27 in approximately its center, link 29 is pivotally secured with one end, while the other end of this link 70 is pivotally secured to the lever 20 intermediate its ends as at 30.

In the slot 28 of the plate 27 a pin 31 of a link 32 travels, which is rotatably secured intermediate its ends in a bracket 33 75 fastened to the side wall of the casing 10. At this point the side wall has a slot 34 through which the arm 35 of the link is extended.

The free end of this arm 35 is pivotally 80 secured as at 36 to a bracket 37 fastened to the side of a T-plate 38 secured with its lower part to a rock shaft 39. The upper ends of the T-bar of the plate 38 are connected by means of springs 40 and 41 respectively to screws 42 and 43 within housings 44 and 45 at the end walls of the casing 10.

Stub shafts 46 and 47 rest with their ends in plate 38 and the ends of these shafts 90 carry nuts 48 and 49. The opposite ends of the shafts are supported in an elongated plate 50 through which they are passed and secured by means of nuts 51 and 52 on their outer ends.

Gears 53 and 54 are secured on the stub shafts 46 and 47, and one of these gears is always in mesh with the gear 24 on shaft 14. It will be clear that the operation of the handle 20 by the intermediary of the 100 links 32 and 35 will work the plate 38 and the stub shaft and gears therein to alternately engage the gear 24.

As shown in Figs. 5 and 6, the pulley 15 is provided with an inner chamber 55 in 105 which a split ring 56 is arranged between the ends of which a lever 57 is provided having a finger 58 adapted to engage a depression 59 of the shaft 14. This position is shown in Fig. 5.

It will be clear that upon the shifting of shaft 14 by the operation of lever 20 and

link 17 the finger 58 will glide upward along the inclined face of the depression 59 and the ring 56 will be expanded to engage frictionally the inner wall of the chamber 55 of pulley 15. The finger 58 will then by means of a sleeve 59' secured to the outer end of the tubular shaft 14' carrying the gear 24 couple the pulley with shaft 14' on which the gear 24 revolves.

10 The device operates as follows—

Upon the operation of the driving shaft 60, the inner end of which is within the rock shaft 39 and which carries a gear 61 secured to the shaft 60 by its bushing 62, the gear 61 will be rotated which is in mesh with both gears 54 and 53 which also will be rotated.

Assumed now that the pin 31 is in neutral or central position in slot 28, neither 20 of said wheels 53 and 54 will be in engagement with wheel 24 on shaft 14', the pulley 15 however will at this time be in neutral position as shown in Fig. 5, and will run idle. If now the lever 20 is operated to bring the pin 31 into engagement with the outer end of the slot 28, by the operation of the T-plate 38, the wheel 24 will be engaged by wheel 53 and the pulley 15 will be coupled to the tubular shaft of 30 wheel 24 in the aforescribed manner, and run in one direction.

If the lever 20 is operated to shift the pin 31 to the opposite and inner end of the slot 28, the wheel 54 will be brought into 35 engagement with the wheel 24 and the pulley will be shifted to run in the opposite direction.

Having thus described my invention what I claim as new and desire to secure by Letters Patent of the United States is as follows—

1. A gear shifting device of the character described comprising a train of gears, a hand lever, and means for operating said 45 gears to rotate the pulley, to run in one or the other direction, said means comprising a sliding plate having a central zig-zag slot, a link pivotally connecting said plate to said hand lever, a two-armed lever pivotally supported in its center, a pin in one of said arms engaging the slot in said plate, a T-plate pivotally connected to the other of 50 said arms, a train of gears adapted to be operated by said hand lever and T-plate for rotating the pulley to run in one or the other direction upon the operation of said lever, and means for moving said gears in and out of 55 their neutral position.

2. In a gear shifting device of the character described, a casing, a rock shaft, a 60 driving shaft connected with said rock shaft, a gear on said rock shaft, a T-plate on said rock shaft to rock therewith, a hand operated lever, an elongated plate, a pair of stub shafts supported in said T-plate and said

elongated plate, a pair of gears on said stub shaft in mesh with the gear on said rock shaft, a shaft in said casing above said T-plate, a gear on said last named shaft adapted to be engaged by one or the other 70 of said gears on said stub shafts upon the rocking of said T-plate upon the operation of said hand lever, to rotate the pulley to run in one and the other direction, and means for moving the gears in and out of 75 their neutral position.

3. In a gear shifting device of the character described, a hand lever, a casing, a tubular shaft revolving in said casing, a gear wheel having a bushing secured to said shaft, a sliding shaft displaceable within said tubular shaft, said sliding shaft having a depression near its outer end, a chambered pulley having a bushing revolving in said tubular shaft, a split ring within the chamber of said pulley, a lever engaging said ring between the split parts thereof, a finger on said lever adapted to engage the depression of said shaft when said pulley is in neutral position and to slide out of said depression to operate said lever to clamp 85 said ring against the inner wall of the chamber of said pulley for coupling said pulley to said tubular shaft to run in one or the other direction upon the operation of said 90 gear by said hand lever.

4. In a gear shifting device of the character described, a rock shaft, a gear on said rock shaft, a T-plate on said rock shaft adapted to rock upon the same, means for 100 rocking said T-plate, an elongated plate, a pair of stub shafts supported in said T-plate and said elongated plate and adapted to rock therewith, springs secured to the ends of the T-bar of said T-plate, incased 105 screws to which the free ends of said springs are fastened, a gear on each of said stub shafts adapted to be engaged by said first named gear, a tubular shaft, a sliding shaft within said tubular shaft, a gear on said tubular shaft adapted to be engaged by one or the other of said stub shaft gears upon the rocking of said T-plate, a pulley, and means connected with said sliding shaft for moving said gears in and out of neutral position, said means being connected with said means for rocking said T-plate for rotating 110 said pulley to run in one or the other direction when not in neutral position.

5. In a gear shifting device of the character described, a casing, a frame secured to the outer wall of said casing, a plate sliding on said frame having a central zig-zag opening, a link pivotally connected to the central outer edge of said plate, a hand lever to 125 which the other end of said link is pivotally connected, a pin sliding in said slot, adapted to be displaced by said hand lever to take up two operating and a neutral position, a rock shaft, a T-plate secured to said rock 130

shaft a bracket secured to said T-plate a two-armed lever, one arm of said lever pivoted to said bracket, a central pivot for said lever, the other arm of said lever carrying 5 said pin, a driving shaft, a gear on said driving shaft, an elongated plate, stub shafts supported in said T-plate and said elongated plate, a gear upon each of said stub shafts in mesh with said first named gear, 10 said T-plate adapted to be rocked in one or the other direction upon the operation of said hand lever, to rock said stub shaft gears, a tubular shaft in said casing, a gear on said tubular shaft adapted to be engaged 15 by one or the other of said stub shaft gears upon the rocking of said T-plate, a pulley on an extension of said tubular shaft adapted to rotate in one or the other direction according to the engagement of the gear on 20 its shaft with one or the other of said stub

shaft gears, a split ring within a chamber of said pulley, a shiftable shaft within said tubular shaft having a depression, a lever for operating said split ring to engage the walls of the pulley chamber, a finger on said 25 lever engaging the depression of said sliding shaft in the neutral position of said pulley, adapted to couple said pulley and said tubular shaft upon the operation of said sliding shaft to bring said finger out of engagement 30 with the depression of said last named shaft, and a link pivotally connected to the end of said sliding shaft and said hand lever for moving said gears out and into their neutral position upon each change in the 35 direction of its rotation.

In testimony whereof I have affixed my signature.

JOHAN VALENT.
